UNITED STATES PATENT OFFICE.

CHARLES H. WILLIAMS, JR., OF CHICAGO, ILLINOIS, ASSIGNOR TO CHICAGO RAILWAY EQUIPMENT COMPANY, OF CHICAGO, ILLINOIS, A CORPORATION OF ILLINOIS.

BRAKE-HEAD.

No. 884,443.

Specification of Letters Patent.

Patented April 14, 1908.

Application filed July 3, 1907. Serial No. 382,024.

To all whom it may concern:

Be it known that I, CHARLES H. WILLIAMS, Jr., a citizen of the United States, residing at Chicago, Cook county, Illinois, have invented 5 a certain, new and useful Improvement in Brake-Heads, of which the following is a full, clear, and exact description, such as will enable others skilled in the art to which it appertains to make and use the same, reference being had to the accompanying drawings, forming part of this specification, in which—

Figure 1 is a detail view of my improved 15 brake head; and Fig. 2 is a similar view of a modified form of brake head.

This invention relates to a new and useful improvement in brake heads, the object being to provide a brake head with a strengthening rib or web across what might be termed 20 the throat portion of the brake head located between the two jaws.

The brake head shown in the accompanying drawings is what is known as the "Christie" head, the jaws and lugs conforming to 25 the templet requirements as prescribed by the Master Car Builders' Association. Brake heads of this type in present use are usually made of malleable iron, and in practice it has been determined that either from improper 30 mounting of the brake shoe in the head or improper setting of the brake head on the beam, the jaws of the brake head are subjected to unusual strains which has developed a weakness in that part of the brake 35 head indicated at A, which I have designated as the throat or connecting portion between the jaws.

Because the brake heads are made of malleable iron it is impracticable in practice to increase the thickness of the metal at the 40 throat portion, due to the liability of the malleableized casting to crack, which cracking results from uneven shrinkage. Therefore, I propose to provide a strengthening web integral with the brake head, which strengthening web may either extend between the 45 key lugs or may continue beyond the key lugs to be connected to the jaws.

My invention consists in providing a brake 50 head with a strengthening web or webs whose function is to reinforce the throat portion of the brake head so that said brake head can withstand heavy strains imposed upon its jaws.

In the drawings, 1 indicates the brake head 55 having the usual jaws 1^a and the usual lugs 1^b. In the construction shown in Fig. 2, strengthening webs 2 integral with the brake head extend between the lugs 1^b, while in Fig. 1 these strengthening webs are continued 60 between the lugs and the jaw members of the brake head so as to provide a continuous reinforcement on each side of the face of the brake head.

I am aware that minor changes in the construction, arrangement and combination of the several parts of my device can be made and substituted for those herein shown and described without in the least departing from the nature and principle of my invention. 65

It is obvious that instead of having the flanges project forwardly from the front face of the brake head said flanges could project laterally from the side faces of the brake head so as to strengthen the throat portion, but as 70 it is desirable to preserve the side lines, I prefer the arrangement shown in the drawings.

Having thus described the invention, what is claimed as new and desired to be secured by Letters Patent is:

1. A brake head provided on its front face 80 with a pair of key lugs, and reinforcing webs connecting said lugs together; substantially as described.

2. A brake head provided adjacent its ends 85 with jaws, key lugs located intermediate said jaws, and reinforcing webs connecting said key lugs together; substantially as described.

3. A brake head provided at its opposite ends with jaws, a pair of key lugs located intermediate said jaws, and reinforcing webs connecting the lugs together and also connecting the lugs and jaws together; substantially as described. 90

4. A cast metal brake head comprising a 95 body portion provided adjacent its opposite ends with jaws, key lugs arranged intermediate said jaws, and reinforcing webs formed integral with the body portion and bridging the space between said lugs; substantially as 100 described.

5. A cast metal brake head having a concaved front face provided with a pair of integral lugs of approximately inverted U-shape, 105 said lugs being spaced away from each other, and reinforcing webs bridging the space between said lugs; substantially as described.

6. A cast metal brake head comprising a

2
body portion provided at its opposite ends with jaws, a pair of lugs of approximately inverted U-shape on said body portion intermediate the jaws, and reinforcing webs connecting the lugs together and also connecting the lugs and jaws together; substantially as described.

In testimony whereof I hereunto affix my signature in the presence of two witnesses, this 26th day of June 1907.

CHARLES H. WILLIAMS, JR.
